AUTOMATIC CURRENT CUTOFF SWITCH
FOR VEHICLES

Stone E. Gray, Hot Springs, Ark.

Application June 12, 1940, Serial No. 340,179

3 Claims. (Cl. 200—52)

This invention appertains to new and useful improvements in automatic switches for vehicles and more particularly to a switch which will operate to cut off current to the various electrical devices and appliances of a vehicle in the event the vehicle turns over in an accident.

An important object of the invention is to provide a switch which when once operated to cut off the current, will remain cut off in spite of the fact that the vehicle again rights itself.

Another important object of the invention is to provide an automatic switch of the character stated which can be easily re-set after it has been automatically operated as a result of antics or contortions of a vehicle during an accident.

These and other objects and advantages of the invention will become apparent to the reader of the following specification.

In the drawings—

Figure 1 represents a top plan view of a starter showing the switch mounted thereon.

Figure 2 is a side elevational view of the switch.

Figure 3 is a sectional view on the line 3—3 of Figure 1.

Figure 4 is a cross section on the line 4—4 of Figure 3.

Figure 5 is a cross section on the line 5—5 of Figure 3.

Figure 6 is a side elevational view of the upper section of the switch with portions broken away.

Figure 7 is a fragmentary detailed sectional view through the upper section of the switch.

Figure 8 is a longitudinal sectional view of the switch showing the conductive material in the outside compartment.

Figure 9 is a longitudinal sectional view of the switch showing the liquid in the outside compartment after the switch has been righted.

Referring to the drawings wherein like numerals designate like parts, it can be seen that numeral 5 represents the lower cylindrical section, while numeral 6 denotes the upper cap section. The lower cylindrical section 5 has the thickened bottom portion *a* bored to snugly but removably receive the lower portion of the tube 7 of insulation. The sections 5 and 6 are also of insulation and as can be seen in Figure 3, the lower end of the tube 7 preferably rests against the blocks 8 of current conductive material. This block 8 is dovetailed into the lower section 5 and has threaded openings thereof registering with threaded openings in the section 5 for the purpose of accommodating suitable screw members which also secure the lower section 5 to the bracket 9 which is secured in place on the starter

structure 10 and to the battery lead 11 by a suitable binding post structure 12.

The lower end of the tube 7 opens over the conical-shaped recess 13 in the top of the block 8.

The cylindrical section 5 above the thickened portion *a* is counterbored to define the outside compartment 14 and a port 15 extends downwardly from the bottom of this compartment 14 to terminate at a level with the opening 16 in the side of the tube 7 which is normally horizontally offset with respect to the port 15.

The upper portion of the section 5 is threaded and engaged into the internally threaded lower portion of the cap section 6. The cap section 6 is of insulation and the tube 7 is of like material and can be formed integrally therewith, the tube depending from the central portion of the top thereof and at that point having a suitable number of openings in the form of slits 17 therein.

The contact or electrode post 18 extends longitudinally in the tube 7 in spaced relation therewith, the same terminating at its lower end above the lower end of the tube and at its upper end being reduced to define a shoulder to abut the underside of the top of the section 6. This reduced portion is threaded and extends through the top of the section 6 to define a binding post on which one or more nuts 19 are disposed.

In the thus defined inner compartment 20 is a volume of current conductive liquid 21. Normally an electrical connection is established between the block 8 and the electrode 18 through the fluid 21. However, in the event the vehicle upon which this switch is mounted turns over, the switch in moving to a horizontal position and beyond such a horizontal position will discharge its liquid content 21 from the inner compartment 20, through the openings 17 into the outer compartment 14, as suggested in Figure 8 and should the vehicle right itself, the liquid will be in the outer compartment 14 and there will be no electrical connection between the block 8 and the electrode 18. Thus the current will be shut off and there will be no chance of liberated gasoline catching fire.

It is a simple matter to re-establish the electrical connection. All that is necessary is to unscrew the cap section 6 slightly so that the opening 16 registers with the port 15 and the conductive liquid 21 will flow downwardly from its position as shown in Figure 9 to the lower portion of the compartment 20.

As can be seen in Figure 6, the lower portion of the tube 7 is beveled as at 22 so that it can seat in the upper portion of the conical recess 13.

It is preferable that the sections 5 and 6 be knurled or grooved as suggested in Figure 2 and denoted by numeral 23 to the end that the same can be easily handled.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. An automatic switch of the character stated comprising a body having a contact in the lower portion thereof, said body being hollow to form a chamber, a cap removably disposed on the body and being of insulation, said cap having a tube depending therefrom and also of insulation, said tube being adapted to depend into the body to the said contact, a contact post extending from the cap and through the tube to terminate in spaced relation with respect to the first-mentioned contact, said tube being formed with an opening adjacent the cap end thereof, said contact post being in spaced relation to the tube to define an inner chamber, and a current conductive fluid normally reposed in the said inner chamber.

2. An automatic switch of the character stated comprising a body having a contact in the lower portion thereof, said body being hollow to form a chamber, a cap removably disposed on the body and being of insulation, said cap having a tube depending therefrom and also of insulation, said

tube being adapted to depend into the body to the said contact, a contact post extending from the cap and through the tube to terminate in spaced relation with respect to the first-mentioned contact, said tube being formed with an opening adjacent the cap end thereof, said contact post being in spaced relation to the tube to define an inner chamber, and a current conductive fluid normally reposed in the said inner chamber, said tube being formed with a port, said cap and tube being rotatable to permit the port to register with the outer chamber to the end that the fluid can flow from the outer chamber to the inner chamber to establish connection between the contact and the contact post.

3. An automatic switch of the character described comprising a body having a contact in the lower portion thereof, said body being hollow to form a chamber, a cap removably disposed on the body and being of insulation, said cap having a tube depending therefrom and also of insulation, said tube being adapted to be bent into the body to the said contact, contact being of a fluid consistency, a contact post extending from the cap and through the tube to terminate in spaced relation with respect to the first mentioned contact, said tube being formed with an opening adjacent the cap end thereof, said first mentioned contact having a downwardly tapering recess therein, the lower edge of the tube being beveled to seat in the said recess, and communicable means between the chamber and the lower interior portion of the tube.
